UNITED STATES PATENT OFFICE.

JOHN B. FRANCIS HERRESHOFF, OF BROOKLYN, ASSIGNOR TO THE NICHOLS CHEMICAL COMPANY, OF NEW YORK, N. Y.

ROASTING-FURNACE.

SPECIFICATION forming part of Letters Patent No. 556,750, dated March 24, 1896.

Application filed March 29, 1895. Serial No. 543,628. (No model.)

To all whom it may concern:

Be it known that I, JOHN B. FRANCIS HERRESHOFF, a resident of Brooklyn, Kings county, State of New York, have invented certain new and useful Improvements in Roasting-Furnaces, of which the following is a specification.

My invention relates to a roasting-furnace of the type commonly employed for roasting ores, &c.; and it consists in the construction and arrangement of parts hereinafter set forth and claimed.

In the drawings, Figure 1 represents a vertical central transverse section through a roasting-furnace embodying my invention. Fig. 2 is a plan view of the floor thereof, the walls of the furnace being in section, the section being taken on line 2 2 of Fig. 1. Fig. 3 is a plan view of a tile forming part of the trays, and Fig. 4 is a section thereof on line 4 4 of Fig. 3. Fig. 5 is a center piece or keystone for the tile-tray hereinafter referred to, of which the tile shown in Fig. 3 forms a part. Fig. 6 is a plan view of another form of tile for constructing another form of tray. Fig. 7 is a section thereof on line 7 7 of Fig. 6. Fig. 8 is a view of a keystone for the tile arch or tray constructed of the species of tile shown in Figs. 6 and 7. Fig. 9 is a plan view 30 of a stirrer, showing the details of the stirrer-arms in dotted lines. Fig. 10 is a side view thereof, partly in section, the section being taken through the hub of the stirrer and serving to exhibit the detailed construction and connection of a stirrer-arm with the hub. Fig. 11 is a section on line 11 11 of Fig. 10, looking in the direction of the arrow.

My invention has special reference to the detailed improvement of roasting-furnaces, 40 which improvements are directed mainly to the attachment of the stirrer-arms to their hub and the construction of the trays or roasting-floors, all of which will be pointed out in the claims.

In the drawings, A represents the wall of 45 the roasting-furnace, which furnace is preferably cylindrical.

B is the roof of the furnace, which is pierced for the reception of an exit-pipe C.

D is the floor of the furnace, and E E' are 50 trays or roasting-floors superposed one above

the other. These roasting-floors are differently constructed, according to the location of their exit-passages. The floors E are constructed of tiles e which are provided with 55 projections e'. These tiles e have their projections e' built into the wall A of the furnace, as shown at e², and bear against a keystone e³ placed in the center of the furnace. There is a space or passage e⁴ formed by the 60 walls of the furnace and the edges of the tiles e. The floors or trays E' are constructed from the tiles d. (Shown in Fig. 6.) These tiles d have their edges built into the wall A of the furnace, as shown at d', and bear against 65 an annular keystone d² at the center of the furnace. This annular keystone forms a passage d³ at the center of the furnace. It will thus be observed that the several floors or 70 roasting-trays are in communication, the passages for such communication being at the edges of the floors E and at the centers of the floors E'.

Openings F are provided in the wall of the furnace opposite each of the several floors or 75 trays. These openings are suitably closed or covered during operation of the furnace, but may be opened at any time to admit of the ready removal or insertion of a stirrer-arm. The lowermost floor of the furnace is provided 80 with exit-pipes a, which are pierced laterally through the walls of the furnace, and with draw-off pipes b, which open downwardly.

In the center of the furnace is a shaft G, which is suitably driven—as, for instance, 85 by means of bevel-gears H—from a suitable source of power. The shaft G is preferably hollow with apertures g near its lowest portion for its cooling-liquid, be the same water or air. The shaft is also provided with a suitable fluid-sealed bearing I. Secured to the shaft at intervals corresponding to the location of the several roasting floors or trays are hubs J, consisting preferably of two sections j, which embrace the shaft and are held together 95 by suitable bolts j². Each of these sections is provided with two cheeks j³ j³, from which project inwardly lips j⁴ j⁴, which have knife-edges for the arm to rest upon, as shown in Fig. 10. Each of the sections is also provided with an 100 overhanging flange j⁵, which is shouldered or recessed, as at j⁶.

K K' are stirrer-arms, each of which is provided with a pair of pins j^7 and an upwardly-projecting toe j^8 . These arms are adapted for engagement with the sections of the hub 5 J, as will be hereinafter described, and are provided with beveled teeth k. The teeth on the arms K and K', which constitute a pair mounted upon a single hub, break joints—that is, they are so arranged that their paths 10 will be staggered—that is to say, when the shaft with its stirrer-arms is rotated, the stirrer-arm K following the stirrer-arm K' will have its teeth k so arranged as to traverse the ridges which were left by the preceding stirrer-arms, so that the material on 15 the trays of the furnace will be very efficiently stirred.

The manner of inserting the stirrer-arms into the hub is as follows: The arm is tilted 20 and its pins j^7 rest upon the lips j^4 , which form a fulcrum for the stirrer-arms. The upwardly-projecting toe of the stirrer-arm is then in proper position to be entered into the recess j^6 of the hub, whereupon the stirrer- 25 arm is lowered to a horizontal position and the toe j^8 entered into the recess j^6 of the hub. The stirrer-arm will now be held firmly in position by its own weight. It will be quite 30 obvious that the stirrer-arms will stir or turn over the material placed upon the roasting floors or trays, the shaft carrying the stirrer-arms being rotated for this purpose.

Coming now to the main utility of my invention, it will be observed that the openings F 35 are so positioned as to allow of the insertion or withdrawal therethrough of the stirrer-arms. These stirrer-arms have hitherto been rigidly connected to the shaft, and in order to remove the same it was heretofore necessary to stop the entire operation of the furnace and to allow it to cool before the workman could get at the fastenings; but by my invention in order to remove the stirrer-arms it is only necessary to stop the rotation of the 40 shaft and bring the desired stirrer-arm into position in line with the opening, when the stirrer-arm may be removed by simply tilting its outermost end, thereby bringing the toe j^8 out of the recess j^6 and permitting the entire 45 arm to be drawn away from the shaft in a horizontal direction and another arm to be rein-

troduced and put in place, when the operation may be resumed. This, it will be obvious, is a great saving of time and labor.

It will also be obvious that by my method 55 of building the roasting floors or trays the labor of supporting the floors by arches and the expense of making special supports for the tiles that was heretofore deemed necessary are obviated. 60

It will likewise be obvious that the details of construction may be varied without departing from the spirit of my invention.

What I claim, and desire to secure by Letters Patent, is— 5

1. In a roasting-furnace, the combination with the main shaft having a hub and having said hub provided with upwardly-projecting lips j^4 , side wings j^3 and with an overhanging flange j^5 , of stirrer-arms K K' having stirrer pins or teeth k, said stirrer-arms being also provided with the upwardly-projecting toe j^8 and with the laterally-projecting pins j^7 , all arranged so that when the parts are assembled the pins j^7 rest on the lips j^4 , the toe j^8 entering 75 beneath the flange j^5 , and so that one or more of the teeth k on the stirrer-arm are nearer the center of the shaft than the pins j^7 .

2. The herein-described roasting apparatus consisting of one or more roasting-floors combined with a vertical main shaft running through the floors, the said shaft having a plurality of hubs, each hub provided with upwardly-projecting lips j^4 , side wings j^3 , and with an overhanging flange j^5 , of a stirrer-arm 85 entered into each hub, each stirrer-arm having stirrer pins or teeth k, said stirrer-arms also provided with an upwardly-projecting toe j^8 and with laterally-projecting pins j^7 , all arranged so that when the parts are assembled the pins j^7 will rest on the lips j^4 and the toe j^8 will enter between the flange j^5 , so that 90 one or more of the teeth k on the stirrer-arms are nearer the center of the shaft than the pins j^7 , and the stirrer will be in position to stir material placed upon the roasting-floor, substantially as described. 95

JOHN B. FRANCIS HERRESHOFF.
